DESCRIPTION

(21) Appl. No.: **29/438,500**

FIG. 1 is a front view of an image of a portion of a display screen with graphical user interface;
FIG. 2 is a front view of a second image thereof;
FIG. 3 is a front view of a third image thereof;
FIG. 4 is a front view of a fourth image thereof;
FIG. 5 is a front view of a fifth image thereof; and,
FIG. 6 is a front view of a sixth image thereof.

(22) Filed: **Nov. 30, 2012**

The appearance of the image transitions sequentially between the images shown in FIGS. 1-6. The process or period in which an image transitions to another forms no part of the claimed design.

(51) **LOC (10) Cl.** 14-04

The broken line showings of portions of a display screen and other features in the figures are environmental only and form no part of the claimed design.
